UNITED STATES PATENT OFFICE

HENRY HOFF, OF MINNEAPOLIS, MINNESOTA

DESIGN FOR A DOOR PLATE

Application filed February 15, 1930. Serial No. 34,566. Term of patent 7 years.

To all whom it may concern:

Be it known that I, HENRY HOFF, a citizen of the United States, residing at Minneapolis, in the county of Hennepin and State of Minnesota, have invented a new, original, and ornamental Design for Door Plate, of which the following is a specification, reference being had to the accompanying drawings, forming part thereof, wherein:—

Fig. 1 is a view in front elevation of my design for ornamental door plate, and

Fig. 2 is a top plan view of the same.

What I claim is:—

The ornamental design for a door plate substantially as shown.

HENRY HOFF.
